METHOD OF FORMING CONCRETE PILES

Thomas C. Bruns, New Orleans, La.

Application January 9, 1947, Serial No. 720,980

8 Claims. (Cl. 61—57)

1

This invention relates to a method of constructing and sinking piles, and more particularly concrete piles for supporting building structures.

It is the more or less common practice to sink preformed concrete piles of various kinds in certain sections of this country, for supporting building structures thereon. The preforming of the piles is disadvantageous for a number of reasons. Many piles are formed of creosoted timber, but in many cases they are formed of precast concrete, particularly when of substantial length and it is quite difficult to handle such piles in transit to the building site and to set them up in position.

It is obvious that relatively long piles, for example piles in excess of thirty feet in length, are quite difficult to handle and are shipped in a horizontal position. Because of the weight of a pile of this character and the shocks to which it is apt to be subjected in handling, it is necessary to use more steel in reinforcing the pile than is required in the use to which it is to be put. Moreover, heavy equipment is required in the handling of such heavy pile structures.

An important object of the present invention is to provide a novel method of constructing and sinking a concrete pile wherein the pile is formed at the exact spot where it is to be used and then directly driven into the ground.

A further object is to provide a novel method of making a concrete pile wherein the pile is formed in the vertical position in which it is to be driven into the ground, and wherein a portion of the pile is formed below the surface of the ground thus minimizing the amount of form work and minimizing the height of the pile above the ground when the driving operation is to be performed.

A further object is to provide such a novel method of the character referred to wherein the precasting of the pile is completely eliminated, thus permitting all of the raw materials to be transported in bulk to the building site and then mixed and poured to form the individual piles.

Other objects and advantages of the invention will become apparent during the course of the following description.

In the drawing I have shown the preferred steps in the carrying out of the method. In this showing

Figure 1 is a sectional view showing the sinking of a boot in the surface of the ground constituting the first step to the method.

Figure 2 is a similar view showing the second

2

step of the method wherein a ground collar and reinforcing elements are placed in position if they are to be used.

Figure 3 is a similar view showing the form for the upper end of the pile in position with the form shown in section and the poured pile in elevation therein.

Figure 4 is a similar view showing the form for the upper pile end, the boot and ground collar in elevation.

Figure 5 is a similar view showing the finished pile in elevation with the forms removed ready for the pile to be driven.

Figure 6 is a view similar to Figure 5 showing the pile driven to its finished position, and

Figure 7 is a plan view of the upper form for the pile.

Referring to Figure 1, the numeral 10 designates the earth into which a pile is to be placed 20 to act as a support for a building structure. A hole 11 extends downwardly into the ground for any desired distance which varies according to the length of the pile to be formed. This hole may be dug or may be formed by driving a suitable plunger in the ground. It is preferred that the hole 11 be formed by driving a suitable sheet steel boot 12 into the ground, the boot remaining in the ground to act as a form for the lower end of the pile in a manner to be described. The boot 12 tapers to decrease the size toward its lower end and has its lower extremity rounded, the general shape shown having been found most suitable for the lower end of the pile to facilitate its being driven into the ground.

As the second step in the method of forming the pile, suitable reinforcing elements 14 may be placed with the lower end thereof projecting downwardly into the boot 12 as shown in Figure 2. The form of the reinforcing may be varied as desired, or the reinforcing may be omitted entirely. If desired, a ground collar 16 of generally tubular form may be employed. This collar is of such size that the lower end thereof contacts with the inner surface of the boot 12 when approximately one-half its length extends into the upper end of the boot.

As the third step in the method, a form indicated as a whole by the numeral 18 is arranged with its lower end contacting the upper end of the boot 12 as shown in Figure 3. The form 18 preferably tapers slightly to decrease in width toward its lower end, as shown, and the lower end of the form substantially fits around the portion of the ground collar 16 which extends above the surface of the ground. The ground collar is

preferably employed for properly centering the form 16 and for preventing the escape of concrete as it is poured into the form.

The form 18 is preferably made of complementary sections 19 (Figures 4 and 7) and these sections may be hinged together at one side as at 20. The opposite edges of the sections may be provided with relatively overlapping lugs 21 receiving wedges 22 for fixing the sections 19 in closed position.

Figure 3 of the drawing actually shows the two successive steps wherein form 18 is placed in position and the concrete poured to form the finished pile, such pile being indicated as a whole by the numeral 25. If reinforcing elements 14 are used, such elements will be embedded in the finished pile 25, as will be apparent. The concrete is poured preferably up to the level of the upper end of the form 18 and the finished pile is thus formed, ready to be driven when properly set and hardened.

Form 18 of each pile thus made is left in position at least until the pile therein has thoroughly set, and it is preferably left in position until after the concrete has thoroughly hardened, the form serving to prevent undue evaporation of moisture if left in position until the pile has hardened. When the pile is thoroughly hardened, the form 18 is removed, thus leaving the finished pile 25 as shown in Figure 5, the lower end of the pile being seated in the boot 12 which has acted as a form for shaping the lower end of the pile. As the final step in the method, a suitable pile driver is employed for driving the pile downwardly into the ground to the proper extent, for example as indicated in Figure 6. It will be apparent that the building erection may be started after all of the necessary piles have been formed and driven into position.

The forms 18 obviously can be used repeatedly and are sufficiently light to be readily handled and transported from site to site. Therefore, these forms need be constructed but once and their repeated use by being removable from the finished piles materially reduces the cost of the latter. The boots 12 remain a permanent part of the driven pile, but since they are formed of relatively thin sheet steel, they do not greatly add to the cost of each pile.

As previously stated, it is the customary practice to use relatively heavy reinforcing 14 to protect precast piles against damage in transportation. This reinforcing as customarily employed is heavier and accordingly more expensive than is required by the pile when in use, and must be used in precast piles even though no reinforcing is necessary in the finished pile. The present method accordingly permits the complete elimination of reinforcing where it is unnecessary in the functioning of the pile as such, and it permits the reduction to a minimum of the amount of reinforcing used where such reinforcing is required. In other words, the present invention eliminates the necessity for having to use any reinforcing, or heavier reinforcing, solely for the purpose of protecting a pile in transit, thus materially reducing the cost of the finished pile. The use of the invention requires no heavy or special equipment, an ordinary crane being sufficient for use both in filling the boot 12 and form 18 with concrete and in driving the pile into final position.

The invention, moreover, completely eliminates the shipping difficulties involved in the handling of every precast pile, the raw material being

assembled as such directly at the site and being mixed at the point required. Moreover, the pile is initially formed in vertical position and at the exact spot where it is to be driven into the ground.

5 I claim:

1. The method of constructing and sinking a concrete pile which comprises preforming an opening in the ground at the point where the pile is to be driven, arranging a form above such opening in alignment therewith, pouring concrete into such form to fill the opening in the ground and the form, and driving the finished pile downwardly into the ground after it has hardened.
- 10 2. The method of constructing and sinking a concrete pile which comprises preforming a hole in the ground, arranging a ground collar in the upper end of such opening with its upper end projecting above the surface of the ground, arranging a form over and in alignment with said hole and surrounding the upper end of said ground collar, pouring concrete into the upper end of said form to fill the hole in the ground, said ground collar and said form, and driving the resultant pile into the ground after it has hardened.
- 15 3. The method of constructing and sinking a concrete pile which comprises preforming an opening in the ground, arranging metal reinforcing of a length generally corresponding to the length of the pile to be formed with the lower end of the reinforcing in said preformed opening, surrounding the upper portion of the reinforcing with a form in alignment with the preformed ground opening, pouring concrete into the form and into the ground opening, removing the form after the concrete has set, and driving the resultant pile into the ground after it has hardened.
- 20 4. The method of constructing and sinking a concrete pile which comprises driving into the ground a preformed boot having a closed lower end, arranging a form in alignment with said boot and in contact with the upper end thereof, pouring concrete into the form and into the boot, removing the form from the resultant pile after the latter has set, and driving the pile into the ground after it has hardened.
- 25 5. The method of constructing and sinking a concrete pile which comprises driving into the ground a preformed boot of sheet material having a closed lower end, arranging a ground collar in the upper end of said boot with its upper end projecting above the surface of the ground, placing a form above and in alignment with the boot and surrounding the upper portion of said ground collar, pouring concrete to fill the boot, ground collar and form, removing the form after the concrete has set, and driving the resultant pile into the ground after it has hardened.
- 30 6. The method of constructing and sinking a pile comprising driving into the ground a preformed boot of sheet material having a closed lower driving end, arranging metal reinforcing of the approximate height of the finished pile with the lower end of the reinforcing in the boot and resting on the lower end thereof, placing a form about the reinforcing above the ground line, pouring concrete to substantially fill the boot and form, removing the form after the concrete has set, and driving the resultant pile into the ground after the pile has hardened.
- 35 7. The method of constructing and sinking a concrete pile which comprises driving a preformed boot of sheet material having a closed

lower end into the ground until the upper end of the boot is substantially even with the surface of the surrounding ground, placing a ground collar with its lower end projecting downwardly into the boot and with its upper end projecting above the ground surface, inserting metal reinforcing of the approximate length of the finished pile with the lower end of the reinforcing supported on the bottom of the boot, arranging a form in alignment with the boot and surrounding the upper end of the ground collar, pouring concrete into the upper end of the form to substantially fill the boot, ground collar and form, removing the form after the concrete has set, and driving the resultant pile into the ground after it has hardened.

8. In the method of constructing and sinking a concrete pile wherein the lower portion of the pile is arranged in the ground, the steps which

comprise arranging above the ground a form having its lower end aligned with the portion of the pile in the ground, pouring concrete into the form to bond and become substantially unitary with the pile portion in the ground, removing the form from the portion of the pile above the ground, and driving the pile downwardly into the ground after it has hardened.
